ADDUCTS OF HETERO CYCLIC AMIDES

Newman M. Bortnick, Oreland, Pa., assignor to Rohm & Haas Company, Philadelphia, Pa., a corporation of Delaware

No Drawing. Filed Dec. 5, 1956, Ser. No. 626,294

5 Claims. (Cl. 260—309.7)

This invention concerns adducts of heterocyclic amides and specific α,β -unsaturated compounds. It further deals with a method of preparation for these adducts.

The heterocyclic amides employed in this invention may be represented by the formula

in which L is a three- to four-membered divalent chain containing two to three carbon atoms and one nitrogen atom, and Y is a chalcogen having an atomic weight of 16 to 32, i.e., oxygen or sulfur. There must be at least two carbon atoms between the nitrogen atoms of the heterocyclic amide considered in a counterclockwise direction. The carbon atoms may have their remaining valences satisfied by hydrogen atoms, by alkyl groups whose total carbon atom content is no greater than eighteen, or by combinations of hydrogen atoms and alkyl groups. When L contains two carbon atoms there are four valences to be satisfied by hydrogen atoms, alkyl groups, or combinations thereof. For instance, there may be four hydrogen atoms, four alkyl groups, three hydrogen atoms and one alkyl group, two hydrogen atoms and two alkyl groups, or one hydrogen atom and three alkyl groups. When L contains three carbon atoms there are six valences to be satisfied by hydrogen atoms, alkyl groups, or combinations thereof and these valences may be satisfied in a way analogous to the manner described above when L contained two carbon atoms. It is also possible for the above-mentioned alkyl substituents to be joined together to form carbocyclic rings in conjunction with the L chain.

The nitrogen atom in the L chain must occupy a position at least two carbon atoms removed from the other nitrogen atom in the heterocyclic amide. It is preferred that it be vicinal to the carbonyl carbon when L contains either three or four members, or when L contains four members the nitrogen atom in L may be one carbon atom removed from the carbonyl carbon. Also, when the nitrogen atom of L is vicinal to the carbonyl carbon atom and L contains three carbon atoms the middle carbon atom of L may contain a hydroxy substituent.

The nitrogen atom in the L chain may have its remaining valence satisfied by a hydrogen atom, an alkyl, including cycloalkyl and alkylcycloalkyl groups of one to eighteen carbon atoms, an aryl, alkylaryl, arylalkyl, or alkylarylalkyl group of six to eighteen carbon atoms, a hydroxyalkyl group of two to eight carbon atoms in which the hydroxy group is no closer than the beta position with respect to the nitrogen atom concerned, an alkenyl group of two to eighteen carbon atoms, an aminoalkyl group of two to eight carbon atoms in which the amino group is no closer than the beta position with respect to the ring nitrogen atom, an alkoxyalkyl group containing up to nineteen carbon atoms in which the alkoxy portion contains up to eight carbon atoms and the alkyl portion contains at least two carbon atoms, an alkenoxyalkyl group of up to nineteen carbon atoms in which the alkenoxy portion contains up to eight carbon

atoms and the alkyl portion contains at least two carbon atoms, a cyano group, and a cyanoalkyl group in which the alkyl part contains up to eight carbon atoms.

The alkyl substituents on the carbon atoms of the L chain may have any possible spatial configuration, such as normal, iso-, tertiary, and the like. Likewise, the alkyl and alkenyl substituents and substituted groups thereof on the nitrogen atom in the L chain may have any possible spatial structure. Also, alkyl groups on saturated or unsaturated cyclic substituents may occupy any possible spatial position. The double bond in the alkenyl groups may be at any possible location.

Typical of the alkyl substituents that may be used to satisfy the remaining valences of the carbon atoms in the L chain include methyl, ethyl, propyl, butyl, hexyl, octyl, decyl, dodecyl, tridecyl, and octadecyl groups.

Typical of the substituents, other than a hydrogen atom, that may satisfy the remaining valence of the nitrogen in the L chain include methyl, ethyl, propyl, butyl, pentyl, hexyl, octyl, nonyl, decyl, dodecyl, tetradecyl, octadecyl, cyclobutyl, cyclopentyl, propylcyclopentyl, octylcyclopentyl, cyclohexyl, butylcyclohexyl, vinyl, allyl, butenyl, pentenyl, hexenyl, heptenyl, octenyl, decenyl, dodecenyl, octadecenyl, phenyl, benzyl, phenylethyl, phenylbutyl, phenyloctyl, phenyldodecyl, butylphenylpentyl, butylphenyl, octylphenyl, dodecylphenyl, naphthyl, naphthylethyl, naphthylbutyl, naphthyloctyl, hydroxyethyl, hydroxypropyl, hydroxybutyl, hydroxypentyl, hydroxyoctyl, aminoethyl, aminopropyl, aminobutyl, aminopentyl, aminoctyl, methoxyethyl, methoxybutyl, methoxyheptyl, methoxydecyl, methoxytetradecyl, methoxyoctadecyl, ethoxyethyl, ethoxybutyl, ethoxyhexyl, ethoxydecyl, ethoxydodecyl, propoxyethyl, propoxypropyl, propoxypentyl, propoxyoctyl, propoxyhexadecyl, butoxyethyl, butoxypropyl, butoxybutyl, butoxyhexyl, butoxyoctyl, butoxydecyl, butoxydodecyl, butoxytetradecyl, pentoxethyl, pentoxypentyl, pentoxbutyl, pentoxdecyl, pentoxydodecyl, pentoxytetradecyl, hexoxyethyl, hexoxypropyl, hexoxybutyl, hexoxyhexyl, hexoxydecyl, hexoxydodecyl, heptoxyethyl, heptoxypropyl, heptoxybutyl, heptoxyheptyl, heptoxyoctyl, heptoxydodecyl, octoxyethyl, octoxyoctyl, octoxynonyl, octoxydecyl, nonoxyethyl, nonoxypentyl, nonoxynonyl, nonoxydecyl, decoxyethyl, decoxypentyl, decoxyheptyl, decoynonyl, undecoxyethyl, undecoxyhexyl, dodecoxyethyl, dodecoxyhexyl, tridecoxyethyl, tridecoxyhexyl, tetradecoxyethyl, tetradecoxypentyl, pentadecoxyethyl, pentadecoxybutyl, hexadecoxyethyl, hexadecoxypropyl, vinoxyethyl, vinoxybutyl, vinoxypropyl, vinoxyhexyl, vinoxyoctyl, vinoxydecyl, vinoxydodecyl, vinoxytetradecyl, vinoxyhexadecyl, alloxethyl, alloxypentyl, alloxoctyl, alloxundecyl, alloxytetradecyl, alloxhexadecyl, butenoxyethyl, butenoxybutyl, butenoxyheptyl, butenoxydecyl, butenoxydodecyl, butenoxypentadecyl, pentenoxyethyl, pentenoxypentyl, pentenoxydecyl, pentenoxytetradecyl, hexenoxyethyl, hexenoxyhexyl, hexenoxydodecyl, hexenoxytridecyl, heptenoxyethyl, heptenoxypropyl, heptenoxyheptyl, heptenoxydodecyl, octenoxyethyl, octenoxybutyl, octenoxyhexyl, octenoxyoctyl, octenoxydecyl, nonenoxyethyl, nonenoxypropyl, nonenoxydodecyl, decenoxyethyl, decenoxypropyl, decenoxybutyl, decenoxyhexyl, decenoxydodecyl, decenoxytridecyl, decenoxyheptyl, decenoxyoctyl, decenoxydecyl, dodecenoxyethyl, dodecenoxyhexyl, tridecenoxyethyl, tridecenoxyhexyl, tetradecenoxyethyl, tetradecenoxypentyl, pentadecenoxyethyl, pentadecenoxybutyl, hexadecenoxyethyl, heptadecenoxyethyl, cyano, cyanomethyl, cyanoethyl, cyanopropyl, cyanobutyl, cyanopentyl, cyanoheptyl, cyanoctyl groups, and the like.

It is preferred that both of the nitrogen atoms in the

heterocyclic amide have a hydrogen atom connected thereto.

Illustrative of the heterocyclic amides that may be employed as reactants in the present invention include

ethyleneurea,
ethylenethiourea,
piperazinone,
piperazinthione,
piperimidinone,
piperimidinthione,
1-ethyl-2-imidazolidinone,
1-cyclohexyl-2-imidazolidinone,
1-dodecyl-2-imidazolidinone,
1-(4-butylcyclohexyl)-2-imidazolidinone,
1-phenyl-2-imidazolidinone,
1-benzyl-2-imidazolidinone,
1-naphthylethyl-2-imidazolidinone,
1-(p-octylphenyl)-2-imidazolidinone,
1-(p-octylphenylethyl)-2-imidazolidinone,
1-(2-hydroxyethyl)-2-imidazolidinone,
1-(6-hydroxyoctyl)-2-imidazolidinone,
1-vinyl-2-imidazolidinone,
1-(3-octenyl)-2-imidazolidinone,
1-(6-octadecenyl)-2-imidazolidinone,
1-(2-aminoethyl)-2-imidazolidinone,
1-(4-aminohexyl)-2-imidazolidinone,
1-(4-methoxyoctyl)-2-imidazolidinone,
1-(6-octoxydecyl)-2-imidazolidinone,
1-(2-vinoxyethyl)-2-imidazolidinone,
1-[4-(6-octenoxy)butyl]-2-imidazolidinone,
1-cyano-2-imidazolidinone,
1-(2-cyanoethyl)-2-imidazolidinone,
1-(6-cyanoethyl)-2-imidazolidinone,
1-octadecyl-2-imidazolidinthione,
1-cyclopentyl-2-imidazolidinthione,
1-phenyloctyl-2-imidazolidinthione,
1-(p-butylphenyl)-2-imidazolidinthione,
1-(4-hydroxybutyl)-2-imidazolidinthione,
1-vinyl-2-imidazolidinthione,
1-(5-decenyl)-2-imidazolidinthione,
1-(8-aminoctyl)-2-imidazolidinthione,
1-(6-ethoxydecyl)-2-imidazolidinthione,
1-(6-vinoxyhexyl)-2-imidazolidinthione,
1-cyano-2-imidazolidinthione,
1-(4-cyanobutyl)-2-imidazolidinthione,
4-propyl-2-piperazinone,
4-decyl-2-piperazinone,
4-cyclohexyl-2-piperazinone,
4-benzyl-2-piperazinone,
4-(p-dodecylphenyl)-2-piperazinone,
4-(4-hydroxybutyl)-2-piperazinone,
4-vinyl-2-piperazinone,
4-(5,5,7,7-tetramethyl-2-octenyl)-2-piperazinone,

The α,β -unsaturated compounds employed in this invention correspond to the formula

in which Q is a hydrogen atom, an alkyl group of one to eight carbon atoms, or the group

to be more fully described hereinafter. T may stand for a cyano group, the group —CONZ₂ in which Z may stand for a hydrogen atom or an alkyl group of one to four carbon atoms, or the group —COOR. The symbol R represents a monovalent esterifying group of preferably one to fourteen carbon atoms and, preferably, alkyl groups of one to fourteen carbon atoms, alkoxyalkyl groups of two to fourteen carbon atoms, aralkyl and alkaralkyl groups of seven to fourteen carbon atoms, and cycloalkyl and alkylcycloalkyl groups of three to fourteen carbon atoms. The alkyl groups may be straight or branched chains in any of the known spatial configurations. The alkyl groups positioned on cyclic structures may occupy any possible ring location.

Typical of the representations of Q include a hydrogen atom, the groups methyl, ethyl, propyl, butyl, hexyl, and octyl, and the groups $-\text{CH}_2\text{CH}_2\text{CH}(\text{CH}_3)-\text{T}$.

Typical of the groups that may be employed as T include cyano, carbamoyl, methylcarbamoyl, ethylcarbamoyl, propylcarbamoyl, butylcarbamoyl, dimethylcarbamoyl, diethylcarbamoyl, dibutylcarbamoyl, methylethylcarbamoyl, ethylbutylcarbamoyl, propylbutylcarbamoyl, methoxycarbonyl, ethoxycarbonyl, propoxy carbonyl, butoxycarbonyl, octoxycarbonyl, dodecoxy carbonyl, tetradecoxycarbonyl, methoxymethoxycarbonyl, methoxydecoxy carbonyl, methoxyoctoxycarbonyl, methoxydecoxy carbonyl, ethoxymethoxycarbonyl, ethoxyethoxycarbonyl, ethoxypropoxycarbonyl, ethoxyoctoxycarbonyl, propoxyethoxycarbonyl, propoxypropoxycarbonyl, propoxy pentoxy carbonyl, propoxyheptoxy carbonyl, butoxymethoxycarbonyl, butoxyethoxycarbonyl, butoxybutoxycarbonyl, butoxyncnoxycarbonyl, butoxydecoxycarbonyl, pentoxymethoxycarbonyl, pentoxybutoxycarbonyl, pentoxypentoxycarbonyl, pentoxyhexoxycarbonyl, pentoxyoctoxycarbonyl, hexoxymethoxycarbonyl hexoxypropoxycarbonyl, hexoxyhexoxycarbonyl, hexoxyoctoxycarbonyl, heptoxymethoxycarbonyl, heptoxybutoxycarbonyl, heptoxyheptoxy carbonyl, octoxymethoxycarbonyl, octoxyethoxycarbonyl, octoxybutoxycarbonyl, octoxyhexoxy carbonyl, benzoxycarbonyl, phenylethoxycarbonyl, phenylbutoxycarbonyl, ethylbenzoxycarbonyl, phenylbutoxycarbonyl, phenylhexoxycarbonyl, phenyloctoxycarbonyl, butylbenzoxycarbonyl, naphthylmethoxycarbonyl, naphthylethoxycarbonyl, naphthylpropoxycarbonyl, naphthylbutoxycarbonyl, cyclopropoxycarbonyl, cyclobutoxycarbonyl, cyclopentoxycarbonyl, octylcyclohexoxycarbonyl, cyclopentylheptoxy carbonyl, and cyclohexyloctoxycarbonyl.

Illustrative of the α,β -unsaturated compounds that may be used as reactants in this invention include acrylonitrile, methacrylonitrile, α -butylacrylonitrile, α -octylacrylonitrile, acrylamide, methacrylamide, α -ethylacrylamide, α -propylacrylamide, α -octylacrylamide, N -methylacrylamide, N,N -dimethylacrylamide, N -ethylmethacrylamide, N -ethyl- N -propylmethacrylamide, N -methyl- α -ethylacrylamide, N -methyl- N -butyl- α -propylacrylamide, N,N -di(2-ethylhexyl)acrylamide, N,N -dimethyl- α -octylacrylamide, methyl acrylate, ethyl acrylate, butyl acrylate, octyl acrylate, dodecyl acrylate, tetradecyl acrylate, methyl methacrylate, butyl methacrylate, decyl methacrylate, methyl ethacrylate, ethyl ethacrylate, octyl ethacrylate, methyl α -propylacrylate, butyl α -propylacrylate, nonyl α -propylacrylate, methyl α -butylacrylate, propyl α -butyl-

acrylate, heptyl α -butylacrylate, methyl α -hexylacrylate, pentyl α -hexylacrylate, undecyl α -hexylacrylate, butyl α -heptylacrylate, methyl α -octylacrylate, dodecyl α -octylacrylate, methoxyethyl acrylate, methoxydecyl acrylate, ethoxypropyl acrylate, butoxyhexyl acrylate, methoxy-methyl methacrylate, propoxydecyl methacrylate, ethoxyethyl ethacrylate, butoxyoctyl ethacrylate, methoxydodecyl α -propylacrylate, pentoxypentyl α -propylacrylate, methoxybutyl α -butylacrylate, butoxyhexyl α -butylacrylate, ethoxyheptyl α -pentylacrylate, methoxyoctyl α -hexylacrylate, propoxybutyl α -heptylacrylate, butoxybutyl α -octylacrylate, benzyl acrylate, naphthylimethyl acrylate, phenylethyl methacrylate, naphthylethyl methacrylate, benzyl ethacrylate, naphthylbutyl ethacrylate, phenyloctyl α -propylacrylate, naphthylethyl α -butylacrylate, octyl-phenylethyl α -pentylacrylate, benzyl α -hexylacrylate, naphthylimethyl α -heptylacrylate, phenylhexyl α -octylacrylate, cyclohexyl acrylate, cyclopentyl methacrylate, cyclohexyl ethacrylate, cyclobutyl α -octylacrylate, dimethyl α -methylene- α' -methyladipate, methyl hexyl α -methylene- α' -methyladipate, dimethoxyethyl α -methylene- α' -methyladipate, hexoxyethyl methyl α -methylene- α' -methyladipate, methyl benzyl α -methylene- α' -methyladipate, dibenzyl α -methylene- α' -methyladipate, methyl cyclohexyl α -methylene- α' -methyladipate, dicyclopentyl α -methylene- α' -methyladipate, methyl octylcyclohexyl α -methylene- α' -methyladipate, ethyl naphthylethyl α -methylene- α' -methyladipate, α -methylene- α' -methyladiponitrile, α -methylene- α' -methyladipamide, N, N'-dimethyl- α -methylene- α -methyladipamide, N,N'-dibutyl- α -methylene- α' -methyladipamide, N-butyl-N'-methyl- α -methylene-adipamide, N,N,N',N'-tetramethyl- α -methylene- α' -methyladipamide, 2-methylene-5-cyanohexanamide, N-methyl-2-methylene-5-cyanohexanamide, N-methyl-N-butyl-2-methylene-5-cyanohexanamide, N,N-diethyl-2-methylene-5-cyanohexanamide, 2-methyl-5-cyano-5-hexenamide, N-methyl-2-methyl-5-cyano-5-hexenamide, N,N-dimethyl-2-methyl-5-cyano-5-hexenamide, N-methyl-N-butyl-2-methyl-5-cyano-5-hexenamide, methyl 2-methyl-5-cyano-5-hexenoate, dodecyl 2-methyl-5-cyano-5-hexenoate, butoxyethyl 2-methyl-5-cyano-5-hexenoate, pentoxypentyl 2-methyl-5-cyano-5-hexenoate, benzyl 2-methyl-5-cyano-5-hexenoate, naphthylethyl 2-methyl-5-cyano-5-hexenoate, cyclohexyl 2-methyl-5-cyano-5-hexenoate, methyl 2-methylene-5-cyanohexanoate, octyl 2-methylene-5-cyanohexanoate, methoxyethyl 2-methylene-5-cyanohexanoate, butoxybutyl 2-methylene-5-cyanohexanoate, octylphenylethyl 2-methylene-5-cyanohexanoate, naphthylbutyl 2-methylene-5-cyanohexanoate, cyclopentyl 2-methylene-5-cyanohexanate, methyl 2-methyl-5-carbamoyl-5-hexenoate, ethyl 2-methyl-5-methylcarbamoyl-5-hexenoate, decyl 2-methyl-5-dimethylcarbamoyl-5-hexenoate, ethoxyethyl 2-methyl-5-methylpropylcarbamoyl-5-hexenoate, octoxybutyl 2-methyl-5-butylcarbamoyl-5-hexenoate, benzyl 2-methyl-5-ethylcarbamoyl-5-hexenoate, cyclohexyl 2-methyl-5-carbamoyl-5-hexenoate, butyl 2-methylene-5-carbamoylhexanoate, tetradecyl 2-methylene-5-carbamoylhexanoate, methoxyhexyl 2-methylene-5-methylcarbamoylhexanoate, butoxypropyl 2-methylene-5-diethylcarbamoylhexanoate, benzyl 2-methylene-5-methylethylcarbamoylhexanoate, naphthylpropyl 2-methylene-5-propylcarbamoylhexanoate, and cyclopentyl 2-methylene-5-dipropylcarbamoylhexanoate.

fined heterocyclic amide and the α,β -unsaturated compound reactants. While the 2:1 adduct is preferred, either type of product is satisfactory for the present purposes.

It is also possible, in some instances, when the nitrogen atom in the L chain of the heterocyclic amide contains a hydroxyalkyl substituent and the α,β -unsaturated compound contains at least one ester group, to obtain a product in which one equivalent of the α,β -unsaturated compound adds to the nitrogen atom of the heterocyclic amide not in the L chain, and another equivalent adds to the hydroxyalkyl substituent by transesterification. These products are quite satisfactory for the present purposes.

The products of this invention are made by bringing together at a reacting temperature in the presence of a strong alkaline catalyst a compound having the formula

with one having the formula

in which the symbols have the significance previously set forth. Temperatures in the range of about 0° to 200° C. are advantageously employed, with a range of about 25° to 175° C. preferred.

The α,β -unsaturated compounds are all liquids and the heterocyclic amides are generally solids. Since at least one of the reactants is always a liquid a solvent is not absolutely necessary. However, in many instances, it is advantageous to employ an inert volatile organic solvent such as methanol, ethanol, butanol, benzene, toluene, xylene, dioxane, diethyl ether, dimethyl ether of ethylene glycol, and the like. At the conclusion of the reaction the solvent is readily removed such as by stripping, preferably at reduced pressures.

The present reaction is exothermic in nature and it is frequently advantageous to conduct the reaction by first adding all of the predetermined equivalent amount of the selected heterocyclic amide reactant to a reaction vessel along with the catalyst and a portion of the predetermined equivalent amount of the α,β -unsaturated compound reactant. In some cases, the above mixture requires some heating in order to initiate the reaction, after which a considerable heat of reaction becomes apparent. As the heat of reaction abates, additional portions of the α,β -unsaturated compound are introduced into the reaction vessel until all of the predetermined amount has been used. By using the above-described procedure, the present reaction is consistently conducted in an orderly manner. In many instances, it is entirely satisfactory to introduce all of the predetermined amounts of both of the reactants, particularly when the reactants have the higher molecular weights or substituent groups occupying considerable molecular space or both, in which situations a retarding ponderal effect is readily observable.

The time of reaction is not critical. Generally, times of about one-half hour to twenty-four hours are used, as conditions indicate. It is usually advantageous to conduct the present method for about an hour or two after the heat of reaction is finally dissipated. This is to maximize yields. Otherwise, the reaction may be concluded as one skilled in the art finds desirable.

A strong alkaline catalyst is used to effect the present method. Typical in this respect are alkali metals such as lithium, sodium, and potassium; alkali metal oxides such as lithium oxide, sodium oxide, and potassium oxide; alkali metal hydroxides such as lithium hydroxide, sodium hydroxide, and potassium hydroxide; alkali metal lower alkoxides such as lithium butoxide, sodium methoxide, and potassium ethoxide; alkali metal hydrides such as sodium hydride and potassium hydride; alkali metal

amides such as sodium amide, lithium amide, and potassium amide; alkali metal lower alkyls and alkenyls such as methyl lithium, ethyl sodium, butyl potassium, allyl sodium, and butenyl potassium; phenylalkyl alkali metals such as benzyl sodium, phenylisopropyl potassium, and alkali metal aromatics such as phenyl sodium, phenyl lithium and phenyl potassium, phenylbutyl sodium; "Alfin" catalysts, which are commercial mixtures of alkali metal alkenyls and alkali metal alkenoxides, such as allyl sodium with sodium allyloxide and butenyl potassium with sodium butenyl oxide; and quaternary ammonium bases such as trimethylbenzylammonium hydroxide and dimethylidibenzylammonium hydroxide and the corresponding alkoxides such as trimethylbenzylammonium butoxide, choline methoxide, and the like.

Yields up to 90% and over are consistently obtained. In some instances if appreciable amounts of impurities are present in the reactants the yields are somewhat reduced. Accordingly, it is preferred to employ reactants 20 of as high a degree of purity as is conveniently and economically feasible.

At the conclusion of the reaction there may be added to the reaction system enough anhydrous mineral acid such as sulfuric, phosphoric, or the like, to neutralize the 25 catalyst. The salt formed may be removed such as by filtration. Otherwise, the reaction system may be washed with water and the aqueous layer separated or decanted when the product is a solid. Any solvent employed may be stripped off, preferably under reduced pressure. Unused reactants when present may be washed out with water or stripped off under reduced pressure. If the product is a liquid it may be distilled, if desired. Solid 30 products may be recrystallized in a conventional manner from a suitable solvent such as hexane, heptane, benzene, toluene, ethylene dichloride, chloroform, or the like.

While the products of this invention may be quite satisfactorily prepared according to the foregoing discussion, it may be advantageous in some instances, where ester groups are concerned and the desired R group is not lower alkyl, to first prepare the lower alkyl ester product 40 and then make the desired higher molecular weight ester product by transesterification. This modification may be used, if desired, to transesterify a single ester group or two ester groups, depending of course on the particular product contemplated.

Transesterification may be conducted preferably in the presence of a strongly acidic esterifying catalyst including sulfuric acid, a lower alkanesulfonic acid, such as butanesulfonic acid, and an arylsulfonic acid, such as p-toluenesulfonic acid. It is, also, possible to employ a strongly 50 acidic ion-exchange resin, such as a sulfonated polystyrene or sulfonated phenolformaldehyde resin.

Transesterification is preferably conducted at the reflux temperature of the reaction mixture, which is usually 55 in the range of about 100° to 275° C., preferably in the range of about 150° to 225° C. The pressure is adjusted, when necessary, to conform to the above temperatures. Also, if desired, small amounts of an inert volatile organic solvent, such as toluene, xylene, or the like, may be used to help regulate the reflux temperature. A lower alkanol is distilled off as the transesterification progresses and the reaction is continued until the theoretical amount is collected.

At the termination of the transesterification, the product is isolated such as by neutralizing the catalyst, filtering, and distilling, preferably under reduced pressure.

The products of this invention have a wide variety of valuable utilities. The lower molecular weight members are excellent solvents for polymers particularly those in which acrylonitrile or a vinyl ester is the major component. The liquid members are useful as synthetic lubricants in which instances they consistently exhibit high viscosity indexes, low pour points, and low volatilities. The present products are useful as plasticizers, particularly for polyvinyl chloride. For instance, a mixture of

30 parts of 1,3-bis(2-methoxycarbonylethyl)-2-imidazolidinone, 45 parts of polyvinyl chloride, 0.75 part of tribasic lead sulfate, and 0.4 part of stearic acid milled for seven minutes at 325° F. gave a tough, flexible film of good quality. Comparable results are obtained with the other products of this invention. The present products are effective fungicides when applied against *Stemphylium sarcinaeforme* and especially *Monilinia fructicola* in concentrations up to 1.0% in an inert carrier. These products are at the same time non-phytotoxic in concentrations approaching 1% as determined on tomato plants in a standard test.

The method and compounds of this invention may be more fully understood from the following examples which are offered by way of illustration but not by way of limitation. Parts by weight are used throughout.

Example 1

There are added to a reaction vessel, equipped with a stirrer, a thermometer, and a condenser, 236 parts of ethyleneurea and three parts of sodium methoxide. A mixture of 622 parts of methyl acrylate and 1.5 parts of hydroquinone is added over a period of 1.25 hours. The temperature of the mixture rises from 30° to 115° C. during the first 25 minutes and is maintained at 85° to 115° C. by intermittent cooling of the reaction vessel. Two-part portions of sodium methoxide are added at approximately 15 minute intervals until a total of eight additional parts is introduced. The reaction is continued for one-half hour and then thirteen parts of anhydrous phosphoric acid is added. The reaction mixture is stripped at reduced pressure and the product is isolated by distillation at 185° to 230° C. at 1 mm. absolute pressure. The product has an n_D^{25} value of 1.4801, contains 10.50% nitrogen (10.85% theoretical), and corresponds to the name 1,3-bis(2-methoxycarbonylethyl)-2-imidazolidinone and the formula

In a similar manner, there are prepared 1-cyclohexyl-3-(2-cyanoethyl)-2-imidazolidinone from 1-cyclohexyl-2-imidazolidinone and acrylonitrile, 1-(p-octylphenyl)-3-(2-carbamoylethyl)-2-imidazolidinone from 1-(p-octylphenyl)-2-imidazolidinone and acrylamide, and 1-(4-methoxyoctyl)-3-[2,5-bis(methoxycarbonyl)-hexyl]-2-imidazolidinone from 1-(4-methoxyoctyl)-2-imidazolidinone and dimethyl α -methylene- α' -methyladipate.

Example 2

There are added to a reaction vessel 22 parts of ethyleneurea and one part of sodium methoxide. There is added 50 parts of ethyl acrylate over a period of six minutes while the reaction mixture is heated to 100° C. Over a period of five hours there are added five portions of sodium methoxide of .25 part each along with ten parts of ethyl acrylate. The temperature of the reaction mixture is slowly increased to 150° C. as the last of the catalyst is added. The temperature is held at 150° C. for an additional hour. The catalyst is neutralized with three parts of phosphoric acid. The product is isolated by distillation at 185° to 205° C. at 0.5 to 0.75 mm. absolute pressure. The product has an n_D^{20} value of 1.4741, contains 9.6% nitrogen (9.79% theoretical), and corresponds to the name 1,3-bis(2-ethoxycarbonylethyl)-2-imidazolidinone and the formula

In an analogous way using potassium amide as the catalyst, there are made 1-octyl-3-(2-decoxy carbonyl-ethyl)-5,5-dimethyl-2-imidazolidinone from 1-octyl-5,5-dimethyl-2-imidazolidinone and decyl acrylate, 1-(2-hy-

droxyhexyl)-3-(2-carbamoylethyl)-4,4,5-trimethyl-2-imidazolidinone from 1-(2-hydroxyhexyl)-4,4,5-trimethyl-2-imidazolidinone and acrylamide, and 1-vinyl-3-(2-cyanopropyl)-4-octyl-2-imidazolidinone from 1-vinyl-4-octyl-2-imidazolidinone and methacrylonitrile.

Example 3

Into a reaction vessel there are added 22 parts of ethyleneurea and 0.25 part of sodium methoxide. Over a ten minute period there is added 64 parts of butyl acrylate. The temperature rises to 50° C. from the exothermic heat of reaction. Twenty minutes after the butyl acrylate is added there is introduced 0.25 part of sodium methoxide and then 0.25 additional part of sodium methoxide after twenty more minutes. The temperature of the reaction mixture is maintained at 110° C. for two and a half hours. The catalyst is neutralized with phosphoric acid and the product is isolated by distillation at 202° to 204° C. at 0.4 mm. absolute pressure. The product has an n_D^{20} value of 1.4711, contains 8.4% nitrogen (8.2% theoretical), and is named 1,3-bis(2-butoxycarbonylethyl)-2-imidazolidinone.

In like manner employing lithium oxide as catalyst, there are prepared 1-[4-(6-octenoxy)butyl]-3-(2-carbamoylpropyl)-2-imidazolidinone from 1-[4-(6-octenoxy)butyl]-2-imidazolidinone and methacrylamide, 1-(8-aminooctyl)-3-(2,5-dibenzylloxycarbonylhexyl)-2-imidazolidinone from 1-(8-aminooctyl)-2-imidazolidinone and dibenzyl α -methylene- α' -methyladipate, and 1-cyano-3-(2-cyanoethyl)-4,4-diethyl-2-imidazolidinone from 1-cyano-4,4-diethyl-2-imidazolidinone and acrylonitrile.

Example 4

There are introduced into a reaction vessel 22 parts of ethyleneurea and 0.25 part of sodium ethoxide. The mixture is heated to 63° C. and 50 parts of methyl methacrylate is added over a period of six minutes causing the temperature to rise above 100° C. There is added after a thirty minute interval 0.25 part of sodium ethoxide and the temperature rises to 136° C. When the heat of reaction subsides the reaction mixture is heated at 120° to 125° C. for three quarters of an hour. Phosphoric acid is added to neutralize the catalyst and the product is isolated by distillation at 175° to 218° C. at 0.3 to 0.75 mm. absolute pressure. The product has an n_D^{20} value of 1.4770, contains 9.9% nitrogen (9.8% theoretical), and is identified as 1,3-bis(2-methoxycarbonylpropyl)-2-imidazolidinone.

In an analogous way using dimethyldibenzylammonium hydroxide as catalyst, there are made 1-methyl-3-[2-dimethylcarbamoylethyl]-5-octadecyl-2-imidazolidinone from 1-methyl-5-octadecyl-2-imidazolidinone and N,N-dimethylacrylamide, 1-(2-vinoxydecyl)-3-(2-dodecoxycarbonylpropyl)-5-dodecyl-2-imidazolidinone from 1-(2-vinoxydecyl)-5-dodecyl-2-imidazolidinone and dodecyl methacrylate and 1-(4-cyanobutyl)-3-(2,5-dibutoxybutyloxycarbonylhexyl)-4-pentyl-2-imidazolidinone from 1-(4-cyanobutyl)-3-pentyl-2-imidazolidinone and dibutoxybutyl α -methylene- α' -methyladipate.

Example 5

There are added to a reaction vessel 86 parts of ethyleneurea and three parts of sodium methoxide. There is added 120 parts of dimethyl α -methylene- α' -methyladipate over a period of ten minutes. The reaction mixture is heated to 70° C. and 1.5 parts of sodium methoxide is introduced. There is added rapidly dropwise 280 parts of dimethyl α -methylene- α' -methyladipate and then one part of sodium methoxide. The reaction mixture is heated at 90° to 110° C. for two hours. There are then added 300 parts of toluene and 100 parts of an aqueous 20% solution of sodium carbonate. The reaction mixture is stirred rapidly and the organic layer is separated, washed with 100 parts of aqueous 10% phosphoric acid, and then washed with 100 parts of water. The organic layer is stripped to

160° C. at 0.1 mm. absolute pressure leaving the product as the residue. The product contains 5.63% nitrogen (5.76% theoretical) and has a saponification number of 466 (461 theoretical). The product is identified as 1,3-bis(2,5-dimethoxycarbonylhexyl)-2-imidazolidinone.

In a similar way using as the catalysts sodium butoxide, sodium hydroxide, and potassium hydride, respectively, there are made 1-(4-aminoethyl)-3-(2,5-dicarbamoylhexyl)-2-imidazolidinone from 1-(4-aminoethyl)-2-imidazolidinone and 2-methylene-5-methyladipamide, 1-(5-decetyl)-3-(2,5-dicyanoethyl)-2-imidazolidinone from 1-(5-decetyl)-2-imidazolidinone and 2-methylene-5-methyladipronitrile, and 1-naphthylethyl-3-(2-carbamoyl-5-cyanoethyl)-4-butyl-2-imidazolidinone from 1-naphthylethyl-4-butyl-2-imidazolidinone and 2-methylene-5-cyanohexanamide.

Example 6

Into a reaction vessel there are added three parts of sodium methoxide and 172 parts of ethyleneurea in 180 parts of toluene. Acrylonitrile, in the amount of 222 parts, is added dropwise over a period of one hour at such a rate that the temperature of the reaction mixture, maintained by the heat of reaction, is kept at 100° to 109° C. The toluene layer is removed and 2.6 parts of anhydrous phosphoric acid is added to neutralize the catalyst. The reaction mixture is stripped and the product is isolated by distillation at 210° to 214° C. at 0.5 mm. absolute pressure. The product contains 29.05% nitrogen (29.15% theoretical) and has an n_D^{25} value of 1.4990. The product is identified as 1,3-bis(2-cyanoethyl)-2-imidazolidinone.

In like manner there are made 1-(3,3,5,5-tetramethyl-2-octenyl)-3-(5-dimethylcarbamoyl-2-cyanoethyl)-4-butyl-2-imidazolidinone from 1-(3,3,5,5-tetramethyl-2-octenyl)-4-butyl-2-imidazolidinone and N,N-dimethyl-2-methyl-5-cyano-5-hexenamide, 1-(3-aminopropyl)-3-[2-benzyloxy-carbonyl-5-propylcarbamoylhexyl]-4,4-dipropyl-2-imidazolidinone from 1-(3-aminopropyl)-4,4-dipropyl-2-imidazolidinone and benzyl 2-methylene-5-propylcarbamoylhexanoate, and 1-cyclohexyl-3-(2-cyclohexoxycarbonyl-5-cyanoethyl)-5,5-dimethyl-2-imidazolidinone from 1-cyclohexyl-5,5-dimethyl-2-imidazolidinone and cyclohexyl 2-methylene-5-cyanohexanoate.

Example 7

There are mixed in a reaction vessel 202 parts of 1-(2-vinoyethyl)-2-imidazolidinone and one part of sodium methoxide. There is then added 74 parts of acrylonitrile in dropwise manner over a period of 22 minutes. The heat of reaction induces a rise in temperature to 70° C. After the heat of reaction subsides there is added 0.5 part of sodium methoxide. After a total time of two hours has elapsed the catalyst is neutralized with sulfuric acid. The product is isolated by distillation at 166° to 168° C. at 0.3 mm. absolute pressure. The product contains 19.9% nitrogen (20.08% theoretical), has an n_D^{25} value of 1.4970, and is identified as 1-(2-vinoyethyl)-3-(2-cyanoethyl)-2-imidazolidinone. This compound may be homopolymerized with Friedel-Crafts catalysts. It may be copolymerized with acrylate esters, maleic anhydride, alkyl fumarates, and other vinyl compounds in the presence of free-radical initiators.

In a similar manner, using sodium as a catalyst, there are prepared 1-vinyl-3-(2-cyanoethyl)-2-imidazolidinone from 1-vinyl-2-imidazolidinone and acrylonitrile, 1-(p-octylphenyl)-3-(2,5-diethoxycarbonylhexyl)-2-imidazolidinone from 1-(p-octylphenyl)-2-imidazolidinone and diethyl α -methylene- α' -methyladipate, 1-(2-benzyloxy-carbonylhexyl)-3,3-dimethyl-4-(p-dodecylphenyl)-2-piperazinone from 3,3-dimethyl-4-(p-dodecylphenyl)-2-piperazinone and benzyl acrylate, and 1-(2-carbamoylpropyl)-3,3-dimethyl-4-(3-cyanopropyl)-2-piperazinone from methacrylamide and 3,3-dimethyl-4-(3-cyanopropyl)-2-piperazinone.

Example 8

There are added to a reaction vessel 65 parts of 1-(2-hydroxyethyl)-2-imidazolidinone, 150 parts of methyl methacrylate and four parts of di- β -naphthol. A solution of 4.5 parts of sodium methoxide in 30 parts of methanol is added slowly while the reaction mixture is heated to reflux and the distillate is removed at a high reflux rate. The head temperature is held at a temperature no higher than 95° C. and the pot temperature is held below 135° C. The reaction is concluded after one hour. The distillate is methanol in amounts equal to the theoretical amount for transesterification. The reaction mixture is shaken with sulfuric acid and then distilled. The product distills at 170° C. at 0.1 mm. absolute pressure. The product contains 56.1% carbon (56.4% theoretical), 10.2% nitrogen (9.4% theoretical), and 7.5% hydrogen (7.4% theoretical). The product is identified as 1-(2-methacryloyloxyethyl)-3-(2-methoxycarbonylpropyl)-2-imidazolidinone and corresponds to the formula

This material gives a hard homopolymer when heated with free-radical generating catalysts. It copolymerizes well with acrylates, acrylonitrile, and other vinyl monomers to give polymers useful as coatings, adhesives, and fibers.

Similarly, there are prepared 1-(6-acryloyloxyethyl)-3-(2-ethoxycarbonylethyl)-2-piperazinone from 1-(6-hydroxyethyl)-2-piperazinone and ethyl acrylate, 1-(8-acryloyloxyoctyl)-3-(2-butoxycarbonylethyl)-2-piperimidinone from 1-(8-hydroxyoctyl)-2-piperimidinone and butyl acrylate, and 1-(4-methacryloyloxybutyl)-3-(2-butoxycarbonylpropyl)-2-piperazinone from 1-(4-hydroxybutyl)-2-piperazinone and butyl methacrylate.

Example 9

To a mixture of 0.5 part of sodium methoxide and 27 parts of 3,3,4,5-tetramethyl-2-piperazinone there is added dropwise 15.5 parts of methyl acrylate. An appreciable heat of reaction is noticed causing the temperature to rise to 65° C. After the heat of reaction abates there is added 0.4 part of sodium methoxide. The reaction mixture is held at 96° C. for three hours after which time 0.8 part of phosphoric acid is added. The product is isolated by distillation. Nitrogen analysis corresponds to 1-(2-methoxycarbonylethyl)-3,3,4,5-tetramethyl-2-piperazinone. The product corresponds to the formula

The corresponding 1,4-bis(2-methoxycarbonylethyl)-3,3-dimethyl-2-piperazinone is made from one equivalent of 3,3-dimethyl-2-piperazinone and two equivalents of methyl acrylate.

Similarly, there are prepared 1,4-bis(2,5-dibenzyl-2-piperazinone from dibenzyl α -methylene- α' -methyladipate and 2-piperazinone, 1-(2-cyanoethyl)-3-decyl-4-[4-(6-decenoxy)hexyl]-2-piperazinone from 3-decyl-4-[4-(6-decenoxy)hexyl]-2-piperazinone and acrylonitrile, and 1-(2-carbamoylethyl)-4-cyano-5-ethyl-6-hexyl-2-piperazinone from 4-cyano-5-ethyl-6-hexyl-2-piperazinone and acrylamide.

Example 10

There are added to a reaction flask 29 parts of ethylene-thiourea and two parts of sodium methoxide. A mixture of 100 parts of methyl methacrylate and two parts of

ing available carbon valences in said L chain being satisfied by members from the group consisting of a hydrogen atom and alkyl groups whose total carbon content is no greater than eighteen, the available valence of said nitrogen atom in said L chain being satisfied by a member from the group consisting of the

group, alkyl, cycloalkyl and alkylcycloalkyl groups of one to eighteen carbon atoms, aryl, alkylaryl, arylalkyl and alkylarylalkyl groups of six to eighteen carbon atoms, hydroxyalkyl groups of two to eight carbon atoms in which the hydroxy group is no closer than the beta position with respect to said nitrogen atom in said L chain, alkenyl groups of two to eighteen carbon atoms, aminoalkyl groups of two to eight carbon atoms in which the amino group is no closer than the beta position with respect to said nitrogen atom in said L chain, alkoxyalkyl groups containing up to nineteen carbon atoms in which the alkoxy portion contains up to eight carbon atoms and the alkyl portion contains at least two carbon atoms, alkenoxyalkyl groups containing up to nineteen carbon atoms in which the alkenoxy portion contains up to eight carbon atoms and the alkyl portion contains at least two carbon atoms, cyano groups, and cyanoalkyl groups in which the alkyl group contains up to eight carbon atoms, Y is a chalcogen having an atomic weight of 16 to 32, and T is a member from the group consisting of a cyano group, the group $-\text{CONZ}_2$ in which Z is a member from the group consisting of a hydrogen atom and alkyl groups of one to eight carbon atoms, and the group $-\text{COOR}$ in which R is a member from the group consisting of alkyl groups of one to fourteen carbon atoms, alkoxyalkyl groups of two to fourteen carbon atoms, aralkyl and alkarylalkyl groups of seven to fourteen carbon atoms, and cycloalkyl and alkylcycloalkyl groups of three to fourteen carbon atoms.

2. An adduct of the compounds

and

having the formula

in which L is a divalent chain of two to three carbon atoms and one nitrogen atom wherein said nitrogen atom

is at least two carbon atoms removed from the other nitrogen atom in the heterocyclic amide when that amide is considered in a counterclockwise direction, the remaining available carbon valences in said L chain being satisfied by hydrogen atoms, the remaining available nitrogen valences in said L chain being satisfied by an alkyl group of 1 to 18 carbon atoms, Y is a chalcogen having an atomic weight of 16 to 32 and R is an alkyl group of one to fourteen carbon atoms.

3. An adduct of the compounds

and

20 having the formula

25 in which L is a divalent chain of two to three carbon atoms and one nitrogen atom wherein said nitrogen atom is at least two carbon atoms removed from the other nitrogen atom in the heterocyclic amide when that amide is considered in a counterclockwise direction, the remaining available carbon valences in said L chain being satisfied by alkyl groups whose total carbon content is no greater than 18, the remaining available nitrogen valences in said L chain being satisfied by an alkyl group of 1 to 18 carbon atoms, Y is a chalcogen having an atomic weight of 16 to 32 and R is an alkyl group of one to fourteen carbon atoms.

4. An adduct of ethyleneurea and a dialkyl α -methyl-40 ene- α' -methyladipate having the formula

45 in which the alkyl portion contains one to fourteen carbon atoms.

5. 1,3 - bis(2,5 - dimethoxycarbonylhexyl) - 2 - imid-50 azolidinone.
